Attorney

UNITED STATES PATENT OFFICE.

GUSTAV A. BISLER, OF PHILADELPHIA, PENNSYLVANIA, ASSIGNOR TO THE UNITED STATES PLAYING CARD COMPANY, OF CINCINNATI, OHIO.

DUPLICATE-WHIST APPARATUS.

SPECIFICATION forming part of Letters Patent No. 616,433, dated December 20, 1898.

Application filed March 27, 1895. Serial No. 543,305. (No model.)

To all whom it may concern:

Be it known that I, GUSTAV A. BISLER, a citizen of the United States, residing in the city and county of Philadelphia, State of Pennsylvania, have invented a new and useful Improvement in Cases for Playing the Game of Duplicate Whist, which improvement is fully set forth in the following specification and accompanying drawings.

My invention consists of a case formed with pockets therein for receiving the "hands" of a game of duplicate whist, said pockets being provided with springs for creating pressure on the cards and preventing their displacement, the parts being adapted to be integral and forming together a serviceable device, as will be hereinafter fully set forth and claimed.

Figure 1 represents a perspective view of a case for playing duplicate whist embodying my invention. Fig. 2 represents a horizontal section on line xx , Fig. 1. Fig. 3 represents a vertical section of a portion on line yy , Fig. 1.

Similar letters of reference indicate corresponding parts in the several figures.

Referring to the drawings, A designates a case formed of the top a , bottom b , and side walls c . Between the walls a and b are partitions B, which, with the adjacent side walls with which said partitions are parallel, form in the interior of the case the pockets C, access to which is had at the cut-away portions D of the side wall c and top a , said pockets being adapted to receive playing-cards, especially for the game of duplicate whist, the rules of which are so well known that it will not be necessary to refer to the same, it being sufficient to say that the hands after being played are placed in said pockets.

In order to prevent the cards from falling out of the pockets, I employ the springs D', which are connected with the bottom b and project toward the top a , from which they are disconnected, so that as the cards are introduced into the pockets the springs first yield and then exert pressure on the cards, the effect of which is evident.

The pockets are located at the corners of the case and the inner sides of the pockets, extending at a right angle to each other, are set back one from the other, the inner ends of the inner side pieces of the pockets joining each other, as at d d' , so that the pockets are

made full depth to accommodate the cards, 55 while reducing the width of the board, as will be apparent on inspection of Fig. 2, said ends d d' forming a post which is united with the top and bottom a b , providing an interior support for the center of the tray.

The top, bottom, and side walls and the springs are formed of celluloid, hard rubber, or other suitable material, which admits of the construction of said springs integral with said bottom or the top, if desired, and all 65 parts may be practically formed integral, producing a light, strong, serviceable, and comparatively thin device for the purpose intended.

If desired, the case may be formed of wood, 70 the springs being suitably secured thereto. The cut-away or removed portions D of the case, together with the recesses D², provide ready means for allowing the cards to be grasped by the thumb and fingers.

Having thus described my invention, what I claim as new, and desire to secure by Letters Patent, is—

1. A case for a game of duplicate whist, consisting of a top and bottom with parallel 80 closed sides, an interior tray forming pockets at the corners of the case, the upper wall of the mouth of each pocket being cut away and the lower wall being recessed, said pockets extending at a right angle to each other and 85 having their inner portions set back from each other.

2. A case for playing the game of duplicate whist, consisting of a top, a bottom, side walls and interior partitions producing pockets 90 at the corners of the case, and having their inner portions set back from each other, the interior of the case being provided with springs integral with the same.

3. A case for playing the game of duplicate 95 whist, consisting of a top, a bottom, side walls, partitions parallel with said side walls, forming pockets at the corners of the case, the pockets being set back from each other at a right angle to each other, the inner walls of 100 the several pockets being joined regularly to each other forming a central support for the tray on the interior thereof.

GUSTAV A. BISLER.
